UNITED STATES PATENT OFFICE.

ALEXANDER S. SPIEGEL, OF CHICAGO, ILLINOIS.

MANUFACTURE OF SHINGLES.

1,172,068.

Specification of Letters Patent. Patented Feb. 15, 1916.

Application filed April 16, 1915. Serial No. 21,867.

To all whom it may concern.

Be it known that I, ALEXANDER S. SPIEGEL, a citizen of the United States, residing at Chicago, Illinois, have invented certain 5 new and useful Improvements in the Manufacture of Shingles, of which the following is a specification.

The present invention pertains to the manufacture of shingles and is intended 10 primarily as an improved method of forming them out of strips of composition roofing material of a well known type.

The object of the invention is an improved process for making notched shingles 15 out of strips of coated or suitably prepared roofing material or shingle stock. The shingles made according to the present invention are of such configuration as to permit their being laid close together and thus 20 prevent the existence of open spaces, as in the case of the ordinary shingles.

A further object of the invention is to so cut the strips of stock into shingles of the desired form as to avoid all waste of material. The simplicity of the operations is such that it can be conducted very rapidly with an enormous output of shingles in a 25 comparatively short interval of time.

A still further advantage which the present 30 method possesses over previous ones is that it produces shingles all of the same shape and size. There are no odd shingles to be used in filling in corners, no imperfectly formed ones, and no reverse ones 35 according to the present invention.

In the accompanying drawing: Figure 1 shows the improved form of shingle. Fig. 2 shows how the shingles are laid in series upon a roof, and Fig. 3 shows a sheet of 40 the material which is cut first into strips and then into shingles.

It is the aim of the invention to produce an attractive form of shingle; one which may be cheaply made without loss of material or waste, and which may be laid close 45 together to prevent any crevices between.

As shown in Fig. 3, a sheet of material of several times the width of a single shingle is used. This sheet is run through 50 a machine provided with suitable cutters, which will slit the material, forming a series of cuts along the lines a' , b , a . Each group of the series consists of two parallel longitudinal slits, a' , a extending on either

side of the center of the strip and connected by a short diagonal slit b . A second set of cutters is carried on the same shaft of the machine which will cut the sheet into straight strips 1, along the lines c . According to this arrangement the adjacent longitudinal slits or cuts a , a' of the several series do not connect, being offset a slight distance from one another. The adjacent ends of these slits a , a' do not terminate at opposite points on the same transverse line (shown at d in dotted lines), but extend slightly beyond it in opposite directions. Thus the ends of the slits a of one series in a sense, overlap the adjacent ends of the slits a' of the next series. The longitudinal strips are now passed in the path of a rotary cutter which cuts transversely or laterally on approximately the lines d severing the strips 1 into separate shingles. By allowing the adjacent ends of the longitudinal slots a and a' to slightly overlap in the direction of the length of the strip, the transverse cuts d can be made with greater rapidity and much more effectively than would be the case if a careful degree 70 of precision and accuracy had to be used to insure exact alinement with the two ends of a and a' .

Great numbers of shingles can be quickly turned out by this method and furthermore, each shingle is an exact duplicate of the other cut from the adjoining piece of the strip. Thus there will be no left hand or right hand shingles, requiring alternate arranging of the layers in constructing the 75 roof.

What I claim is:—

A process of making shingles comprising longitudinally slitting a strip of material having parallel sides, intermittently on opposite sides of its center line, with the alternate adjacent ends of pairs of slits connected by cuts substantially transverse to the length of the strip while overlapping the other ends, then continuously cutting 100 the strip transversely through the overlapped ends.

In testimony whereof, I affix my signature in presence of two witnesses.

ALEXANDER S. SPIEGEL.
